UNITED STATES PATENT OFFICE.

HORACE D. EDDY, OF GLENVILLE, OHIO, ASSIGNOR OF ONE-HALF HIS RIGHT
TO JAMES M. GRAY, OF SAME PLACE.

IMPROVEMENT IN BED-BOTTOMS.

Specification forming part of Letters Patent No. 151,211, dated May 26, 1874; application filed
March 26, 1874.

To all whom it may concern:

Be it known that I, HORACE D. EDDY, of Glenville, in the county of Cuyahoga and State of Ohio, have invented certain new and useful Improvements in Bed-Bottoms; and I do hereby declare the following to be a full, clear, and exact description of the invention, such as will enable others skilled in the art to which it pertains to make and use it, reference being had to the accompanying drawings, which form part of this specification.

The nature of my invention relates to an improvement in bed-bottoms; and consists in the combination and arrangement of the several parts hereinafter more fully described and then pointed out in the claim, whereby a simple, cheap, and durable spring bed-bottom is provided.

In the drawings, Figure 1 is a plan view, and Fig. 2 a longitudinal vertical sectional view, of my invention.

a are two longitudinal base-boards, to which are secured the two cross supporting-bars *b*, thus forming a substantial frame, *F*, to which are secured the springs. The bars *b* are beveled to a sharp edge, and are made of thoroughly-seasoned wood, or are capped with metal. *c*, *d*, and *e* are longitudinal flexible slats or bars so combined as to form the bed-springs. The slats *c* and *d* are riveted together at their ends, and form the elliptical springs *S*. The slat *d* is made slightly longer than the slat *c*, so that when the ends of the two slats are riveted together the curvature of slat *d* will be greater than the curvature of slat *c*, which gives it greater strength, and does not impair its flexibility. Between the strips *c* and *d*, and near the ends, are inserted the bars *f*, which bars are in length equal to the width of the bed-bottom to be made. These bars are so inserted as to press the slats *c* and *d* apart and give the spring an elliptical form, and serve also as fulcrums or supports for the slat *c*, and prevent "setting" or breaking down of the slats. Having constructed the desired number of elliptical springs *S*, and having inserted the bars *f*, as described, the springs, being arranged at equal distances on said bars,

are secured by screws passing through into said bars. On the upper side, at the center, and secured, by screws or other suitable means, to the strips *d*, is the bar *g*, over which the supporting spring-strips *e* are passed, said strips *e* being secured to said bar by screws or other suitable means. The strips *e* are made somewhat longer than the strips *c*, so that when bent, as hereinafter described, their ends will be flush with the ends of elliptical springs *S*, and rest on the supporting-bar *b*. These strips number one less than the springs *S*, and are arranged alternately between said springs. The strips *e* have their ends bent downward, and are held in place by the bars *h*, to which they are secured by screws, and the bars *h* are so placed as to hold the ends of said strips *e* at a point flush with the ends of the springs *S*, and so that they will rest on the bar *b*. The bars *h* serve not only to hold the springs *e* in proper position, but also as a fulcrum against which the said strips, in their reflexive action, bear. The two outer strips *e* are slotted at *i*, and provided with thumb-screws, which secure them to the supporting-bars *b*.

It will be seen that when the flexible strips are secured together by the bars *f*, *g*, and *h*, a substantial spring-frame is formed, which is not liable to sag or give way laterally. It will be further seen that when said spring-frame is secured to the frame *F* a spring bed-bottom of great strength, durability, and simplicity is formed, and one which presents the requisites of comfort in such class of inventions.

Having described my invention, what I claim, and desire to secure by Letters Patent, is—

The combination of the springs *S* with the frame *F* by means of the flexible strips *e* and bars *g* and *h*, substantially as set forth.

In testimony that I claim the foregoing I have hereunto set my hand this 23d day of March, 1874.

HORACE D. EDDY.
